CLAIM

The ornamental design for a tubing clamp, as shown and described.

DESCRIPTION

FIG. 1 is a front, right perspective view of a tubing clamp shown in a closed configuration;

FIG. 2 is a rear, left perspective view thereof;

FIG. 3 is a front, left perspective view thereof;

FIG. 4 is a rear, right perspective view thereof;

FIG. 5 is a front, right perspective view of the tubing clamp shown in an open configuration;

FIG. 6 is a rear, left perspective view thereof;

FIG. 7 is a front, left perspective view thereof; and,

FIG. 8 is a rear, right perspective view thereof.
